UNITED STATES PATENT OFFICE.

GEORGE W. LEWIS, OF PORTSMOUTH, VIRGINIA, ASSIGNOR OF TWO-THIRDS
TO ALEXANDER P. GRICE AND LEROY C. GODWIN, OF SAME PLACE.

SEAL-LOCK.

SPECIFICATION forming part of Letters Patent No. 408,886, dated August 13, 1889.

Application filed November 6, 1888. Serial No. 290,116. (Model.)

To all whom it may concern:

Be it known that I, GEORGE W. LEWIS, a citizen of the United States, residing at Portsmouth, in the county of Norfolk and State of Virginia, have invented a new and useful Improvement in Car Seal-Locks, of which the following is a specification.

My invention relates to car seal-locks; and it consists in a certain novel construction and combination of devices, fully described hereinafter in connection with the accompanying drawings, and specifically pointed out in the claims.

In the drawings, Figure 1 is a perspective view of the seal-lock embodying my improvements applied in the operative position to a car-door. Fig. 2 is a face view of the stationary base-plate with the revoluble disk removed. Fig. 3 is a perspective view of the revoluble disk, showing its inner side. Fig. 4 is a longitudinal central sectional view of the seal in its operative position. Fig. 5 is a plan view of a modified form of the seal applied in the operative position to a car-door. Fig. 6 is a detail section through the engaging flange of the disk. Fig. 7 is a detail view of the gravity-pawl. Fig. 8 is a transverse section of Fig. 5.

Referring by letter to the drawings, A designates a car-door provided with a staple B, which is engaged by a slot c in the free end of a hasp C of any preferred design.

D represents a stationary base-plate secured by screws or bolts d d to the car-door adjacent to the hasp and provided at its center with a square boss E, in the center of which is formed a recess F.

G designates a revoluble disk having a central perforation g, registering with a central perforation e in the base-plate, and a pin or rivet H passes through the said registering-perforations and pivots the revoluble disk centrally on the base-plate. The revoluble disk is provided at one side with a triangular opening I, the base i of which may be arranged flush with either side of the square boss on the base-plate, and a pin K is arranged on the base-plate in such a position that when the disk is turned to the position indicated in dotted lines in Fig. 1 the pin will be visible through the triangular opening. When the

disk is in any other position, the outer end of the pin is covered, as shown in Fig. 4. The disk is further provided with a peripheral inwardly-extending flange L, which operates at 55 its inner edge close to the surface of the base-plate, and therefore when the triangular opening is out of alignment with the pin the latter is completely concealed by the flange.

The revoluble disk is provided on the side 60 adjacent to the opening I with a flat ear M, which is adapted to be arranged over and bear on the hasp of the door and prevent the free end of the latter from being removed from the staple, as shown in Fig. 1, and the disk is 65 also provided on the opposite side from the triangular opening with an inwardly-extending detent or projection N, which operates at its free end in an annular groove N' in the outer side of the base-plate.

A boss O on the inner side of the revoluble disk projects into the center of the recess F in the base-plate, and is provided with two or more ratchet-teeth or shoulders f f; and P represents a gravity-pawl pivoted in the recess F and engaging the said ratchet-teeth or shoulders to prevent the rotation of the disk in the reverse direction to that indicated by the arrow in Fig. 1.

Having arranged the seal in the position 80 indicated, turn the revoluble disk to the position shown in dotted lines in Fig. 1, pass one end of a seal-tag Q under the edge of the disk and engage a suitable perforation q therein with the pin K, the triangular opening I in the disk enabling this adjustment to be readily accomplished. Then turn the disk in the direction indicated by the arrow in Fig. 1 until its ear M bears on the hasp, in which position it will be held by the pawl-and-ratchet connection between the disk and the base-plate. In this position of the revoluble disk the detent or projection N is close to the upper edge of the seal-tag, so that if the attempt is made to raise the ear to release the hasp the said projection or detent will bear against the said tag. The inner end of this seal-tag, which is preferably square, fits snugly against the adjacent side of the square boss, and therefore it will be evident 95 that the pressure of the detent or projection on the upper edge of the seal-tag, caused by

the rotation of the disk, will tear or twist or bend the former and indicate to the proper authorities that the lock has been tampered with. This seal-tag should be made of cardboard, celluloid, sheet metal, or similar material, which will be readily bent or broken, and thereby permanently indicate that the disk has been turned.

In the modification shown in Fig. 5 the seal-tag is substituted by a thin metal loop R, whose ends are perforated and fitted over the pin K, in which case the ear described in the other form is dispensed with and the disk is provided with a suitable knob or handle S to enable it to be turned. In the modification, as in the first form, the efficiency of the seal-tag resides in the fact that the disk cannot be rotated in one direction because of the pawl-and-ratchet connection, and cannot be rotated in the other direction without breaking or injuring the seal-tag, which in this case consists of the loop, and therefore any attempt to remove the seal-tag or open the door may be readily detected. The loop may be supplemented by an ordinary seal, which may fit on the stud K either above or below the loop R. Division-strips N² are formed on the base-plate to prevent access to the pawl by a knife or other instrument employed in picking locks.

Having thus described my invention, I claim—

1. In a car seal-lock, the combination, with the base-plate having a stationary pin K to receive the seal-tag, of the revoluble disk mounted on the base-plate and capable of revolution in one direction only, the said disk covering the free end of the pin to prevent the removal of the seal-tag, and provided with a detent or projection adjacent to the latter, and the pawl-and-ratchet connection between the disk and the base-plate to prevent a reverse rotation of the former, substantially as specified.
2. In a car seal-lock, the combination, with the base-plate having a stationary pin K to receive a seal-tag, of the revoluble disk mounted on the base-plate and covering the free end of the said pin, and provided with a detent or projection, the tag extending under the disk adjacent to the detent or projection, and means to prevent the disk revolving in one direction, substantially as specified.
3. In a car seal-lock, the combination of the

base-plate provided with a pin to engage a suitable seal-tag, the revoluble disk mounted on the base-plate over the free end of the pin K, and provided with an opening I, adapted to register with and expose the said pin, the disk being further provided with a detent or projection adjacent to the seal-tag to engage and thereby tear or disfigure the latter when the disk is turned, and the pawl-and-ratchet connection between the disk and the base-plate, substantially as specified.

4. In a car seal-lock, the combination of the base-plate provided with a square boss and having a pin K adjacent to one side of the boss to receive the seal-tag, which is provided with a perforation to engage the pin and a square end to bear against the boss, the revoluble disk mounted on the base-plate and provided with a peripheral flange L, fitting at its inner edge close to the base-plate, and a detent or projection N to bear against the edge of the said seal-tag, and the pawl-and-ratchet connection between the disk and the base-plate, substantially as specified.

5. In a car seal-lock, the combination, with the base-plate provided with a pin K, adapted to have a seal-tag engaged therewith and having an annular groove near its outer edge, of the revoluble disk mounted on the base-plate and provided with a detent or projection N, operating in the said groove, the boss on the inner side of the disk, projecting into a recess in the base-plate, and provided with ratchet-teeth or shoulders, and the gravity-pawl arranged in the said recess and engaging the teeth or shoulders, substantially as and for the purpose specified.

6. In a car seal-lock, the combination of the base-plate having a seal-tag fixed thereto, the revoluble disk mounted on the plate and provided with a detent or projection to engage the seal-tag, the pawl-and-ratchet connection between the disk and plate, and the ear on the disk extending over the hasp of the car-lock to prevent the disengagement of the latter, substantially as described.

In testimony that I claim the foregoing as my own I have hereto affixed my signature in presence of two witnesses.

GEORGE W. LEWIS.
